[57] CLAIM

The ornamental design for combined lamp and picture frame, as shown and described.

DESCRIPTION

FIG. 1 is a front elevational view of a combined lamp and picture frame showing my new design;
FIG. 2 is a left side elevational view thereof, the right side being a mirror image thereto;
FIG. 3 is a bottom plan view thereof; and
FIG. 4 is a top plan sectional view thereof taken substantially along section line 4—4 on FIG. 2.
